Inventor:

Edward A. Kunz,

UNITED STATES PATENT OFFICE.

EDWARD A. KUNZ, OF WILMETTE, ILLINOIS.

REPRODUCING HALF-TONE PRINTING PLATES.

Application filed May 8, 1922. Serial No. 559,485.

To all whom it may concern:

Be it known that I, EDWARD A. KUNZ, a citizen of the United States, residing at Wilmette, in the county of Cook and State 5 of Illinois, have invented certain new and useful Improvements in Reproducing Half-Tone Printing Plates, of which the following is a specification.

The present invention relates to improvements in reproducing half-tone printing plates.

More particularly, the present invention relates to processes for making enlarged copies, or duplicates, or reduced copies of 10 so-called half-tone, line or color process printing plates, one object of the invention being to materially reduce the cost of reproducing said plates.

According to present practice, when it is 15 desired to reproduce a printing plate, an entirely new photograph is made on the scale desired, which photograph is applied to the printing plate and subjected to the etching process. For various reasons, which 20 need not be recited in detail herein, the etched plate must be finished by means of very laborious and expensive hand work in order to bring out the proper tones, values, detail, etc. According to the processes as 25 now known and used, the production of any subsequent plates is practically as expensive as the production of the first printing plate. According to the present invention, however, a very considerable saving is accomplished 30 in the production of subsequent printing plates in a manner which will be clear as the description proceeds. The present invention is employed more particularly 35 in the making of enlarged plates, though, it will be understood, it is also applicable to the reproduction of printing plates on any desired scale. The one figure 40 of the drawing represents, on an enlarged scale, a cross sectional view of a half-tone printing plate and an inking roller illustrating 45 the principles of the present invention.

According to the present invention, after the original printing plate has been made, subsequent plates may be produced substantially according to the process which may be described as follows: First the original plate is thoroughly cleaned with acid, lye, water, or other cleaning agent to remove all foreign substances, leaving the metal perfectly clean. 50 A fine white magnesia or French chalk is rubbed into depressions or bottoms until all

the gradations of color, detail, design and the like are clearly defined, the printing surface being rubbed and cleaned so as to be free from chalk, that is to say, the projecting portions, or printing surface, of the plate are cleaned while the depressions are covered with the chalk. The chalk may then be hardened by any of the well known processes for that purpose and the plate 55 may be rolled up with ink, usually black. Particular attention should be directed to the advantages of hardening the chalk or other substance located in the depressions or bottoms. The hardening process will not 60 only facilitate ease in handling the printing plate but has the further advantage that the chalk or other substance in the depressions or bottoms will shrink slightly, whereby the printing dots will be cleanly presented. The 65 printing surface will project slightly above the surface of the chalk, whereby the printing surface, and only the printing surface, is evenly covered with ink. A picture is thereby created in black and white of the 70 subject which appears on the plate, which picture is now ready for photographing. The prepared plate is now photographed to the desired size for the new plate, the resulting photograph being applied to a sensitized blank and subjected to the etching 75 process. Any line, dot or detail appearing on the original plate will be reproduced upon the new plate. It will be understood 80 that though magnesia or chalk, which are 85 white in color, and ink, which may be black, are mentioned herein, other materials may be used, provided they contrast photographically.

The approved process according to the 90 present invention is especially desirable in the making of enlarged printing plates from the so-called colotype or three or four color process engravings. Inasmuch as all details of the original plate are sharply defined in the new plate, subsequent manipulation is minimized, whereby the cost of 95 reproducing the original plate is reduced to a minimum.

The present invention is to be distinguished 100 from the process of photographing a proof made by the original plate and using the resulting photograph by applying same to the printing plate under preparation. This process has been found to be objectionable 110 for the reason that same is inaccurate.

One embodiment of the present invention

has been described in detail. Many modifications will occur to those skilled in the art. It is intended in this patent to cover all such modifications that fall within the scope of the invention as defined by the appended claims.

I claim:

1. Steps in the improved process of reproducing a printing plate consisting in rubbing chalk upon said plate to fill up the depressions thereof but leaving the printing surface clean, hardening said chalk, rolling up the printing surface with black ink and photographing the treated plate.
2. A step in the process of reproducing a printing plate which consists in thoroughly cleaning same and rubbing chalk into the depressions thereof but leaving the printing

surface clean, hardening said chalk and rolling up upon said printing surface a material contrasting photographically with said chalk.

3. The improved process relating particularly to the enlargement of printing plates which consists in filling the depressions in a printing plate with one substance, hardening said one substance, and covering the printing surface with a substance contrasting photographically with the first mentioned substance, photographing the treated plate and using the resulting negative for the production of a new plate.

Signed at Chicago, Illinois, this 28th day of April, 1922.

EDWARD A. KUNZ.
